(57) **CLAIM**

The ornamental design for a casing for data processing equipment, as shown and described.

DESCRIPTION

FIG. 1 is a front perspective view of a casing for data processing equipment in accordance with our new design; FIG. 2 is a front view thereof;

FIG. 3 is a rear perspective view thereof;

FIG. 4 is a rear view thereof;

FIG. 5 is a right side view thereof;

FIG. 6 is a left side view thereof;

FIG. 7 is a bottom plan view thereof; and,

FIG. 8 is a top plan view thereof.

The broken lines depict portions of the casing for data processing equipment in which the design is embodied that form no part of the claimed designed.
